US0D1103121S

(12) **United States Design Patent** (10) **Patent No.:** **US D1,103,121 S**
(45) **Date of Patent:** **** Nov. 25, 2025**

(54) **ELECTRIC CONNECTOR**

(71) Applicant: **Moлекс, LLC**, Lisle, IL (US)

(72) Inventor: **Guo-Li Li**, Shanghai (CN)

(73) Assignee: **Moлекс, LLC**, Lisle, IL (US)

(**) Term: **15 Years**

(21) Appl. No.: **29/919,840**

(22) Filed: **Dec. 6, 2023**

(30) **Foreign Application Priority Data**

Jun. 7, 2023 (CN) 202330347769.0

(51) **LOC (15) Cl.** **13-03**

(52) **U.S. Cl.**

USPC **D13/147**

(57) **CLAIM**

The ornamental design for an electric connector as shown and described.

DESCRIPTION

FIG. 1 is a front top perspective view of an electric connector showing my new design;

FIG. 2 is a rear bottom perspective view thereof;

FIG. 3 is a front view thereof;

FIG. 4 is a rear view thereof;

FIG. 5 is right side view thereof;

FIG. 6 is a left side view thereof;

FIG. 7 is a top view thereof; and,

FIG. 8 is a bottom view thereof.

1 Claim, 7 Drawing Sheets
